COVER FOR TOWEL CABINET

Erwin B. Bahnsen, Oak Brook, Ill., assignor to
Steiner American Corporation

Filed Aug. 24, 1973, Ser. No. 391,348

Term of patent 14 years

Int. Cl. D6—06

U.S. Cl. D6—96

FIG. 1

FIG. 2

FIG. 3

FIG. 5

FIG. 4

FIG. 1 is a front elevational view of a cover for towel cabinet showing my new design;

FIG. 2 is a side elevational view of the cover for towel cabinet of FIG. 1;

FIG. 3 is a top elevational view of the cover for towel cabinet of FIG. 1;

FIG. 4 is a bottom elevational view of the cover for towel cabinet of FIG. 1; and

FIG. 5 is a rear elevational view of the cover for towel cabinet of FIG. 1.

I claim:

The ornamental design for a cover for towel cabinet, as shown.
